(57) **CLAIM**

The ornamental design for a display screen with animated graphical user interface, as shown and described.

DESCRIPTION

FIG. 1 is a front view of a first image of a first embodiment of the display screen with animated graphical user interface showing my new design;

FIG. 2 is a front view of a second image thereof;

FIG. 3 is a front view of a third image thereof;

FIG. 4 is a front view of a fourth image thereof;

FIG. 5 is a front view of a fifth image thereof;

FIG. 6 is a front view of a sixth image thereof;

FIG. 7 is a front view of a seventh image thereof;

FIG. 8 is a front view of an eighth image thereof;

FIG. 9 is a front view of a ninth image thereof;

FIG. 10 is a front view of a first image of a second embodiment of the display screen with animated graphical user interface;

FIG. 11 is a front view of a second image thereof;

FIG. 12 is a front view of a third image thereof;

FIG. 13 is a front view of a fourth image thereof;

FIG. 14 is a front view of a fifth image thereof;

FIG. 15 is a front view of a sixth image thereof;

FIG. 16 is a front view of a seventh image thereof;

FIG. 17 is a front view of an eighth image thereof; and,

FIG. 18 is a front view of a ninth image thereof.

The appearance of the images sequentially transitions between the images shown in FIGS. 1 to 9, and FIGS. 10 to 18. The process or period in which an image transitions to another forms no part of the claimed design.

The broken lines illustrate a display screen and form no part of the claimed design.
